Primary Examiner — T. Chase Nelson*Assistant Examiner* — Michelle E Wilson(74) *Attorney, Agent, or Firm* — Ballard Spahr LLP**CLAIM**

The ornamental design for a ribbon display device for a cord, as shown and described.

DESCRIPTION

FIG. 1 is a perspective view of a ribbon display device for a cord of the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
